UNITED STATES PATENT OFFICE

ALBERT G. SAURWEIN, OF CLEVELAND, OHIO

DESIGN FOR AN ELECTRIC ARC LAMP

Application filed August 28, 1929. Serial No. 32,569. Term of patent 7 years.

To all whom it may concern:

Be it known that I, ALBERT G. SAURWEIN, a citizen of the United States, residing at Cleveland, in the county of Cuyahoga, State of Ohio, have invented a new, original, and ornamental Design for an Electric Arc Lamp of which the following is a specification, reference being had to the accompanying drawing, forming part thereof, and wherein the single figure is a per-

spective view of an electric arc lamp showing my new design.

The part of the lamp not shown by the drawing is of the same configuration as the front, and has no distinctive features.

I claim:

The ornamental design for an electric arc lamp substantially as shown and described.

ALBERT G. SAURWEIN.
